STICK DISPENSING MACHINE

Ralph F. Anderson, Rockford, Ill.

Application April 8, 1949, Serial No. 86,154

13 Claims. (Cl. 226—14)

1

This invention relates to dispensers and more particularly to dispensers for confectionary sticks.

An object of the present invention is the provision of a dispenser having increased capacity.

Another object of the invention is the provision of a dispenser of the above character having novel means for controlling the actuation of the stick feeders.

Another object of the invention is the provision of a dispenser of the above character having novel means for controlling the stick feeders in the event of jamming of sticks in the feeders.

Another object of the invention is to provide a dispenser of the above character having a plurality of rows of spaced stick feeders with novel means movable between preselected positions adjacent the feeders capable, in each of said positions, of guiding and holding sticks ejected from said feeders in a manner to be readily received by a stick holder.

Another object of the invention is the provision of a dispenser wherein a stick guide means is mounted adjacent the feeders for movement thereof between opposed positions to effect alignment of alternate portions thereof with the stick feeders and for pivotal movement thereof about an axis to an inoperative position for access to the stick feeders.

Another object of the invention is to provide a dispenser having a novel stick guide means for retaining the sticks received therein from the stick feeders in a position to be readily received by a stick holder.

Another object of the invention is the provision of a dispenser having means to prevent operation of the feeders unless the stick guide means is properly aligned with the stick feeders.

Other objects and advantages of the invention will become apparent from the following detailed description taken in connection with the accompanying drawings, in which—

Figure 1 is a fragmentary perspective view of a stick dispenser embodying the present invention;

Fig. 2 is a fragmentary sectional view taken substantially on the line 2—2 of Figure 1 showing a stick guide support plate in one loading position in which alternate rows of the stick guides are in alignment with the feeders and have received ejected sticks therefrom;

Fig. 3 is a view similar to Fig. 2 showing the plate moved to the opposed loading position wherein the remaining rows of stick guides are in alignment with the feeders and have received sticks therefrom;

2

Fig. 4 is a fragmentary side elevational view of the dispenser with portions of the cabinet cut away to show construction details;

Fig. 5 is a perspective view partly in section showing the construction of a jam release and push rod return switch;

Fig. 6 is a sectional view taken substantially along the line 6—6 of Fig. 4;

Fig. 7 is a fragmentary rear elevational view 10 showing the mounting for the stick guide support plate and the arrangement of a pre-positioning switch interconnected in the main circuit for preventing operation of the stick feeders until the plate is in a position in alignment with the feeders;

Figs. 8 and 9 are side sectional and end views, respectively, showing the details of construction of a stick guide and its mounting on the support plate;

Figs. 10 and 11 show an alternate construction of a stick guide and a mounting therefor;

Fig. 12 is a wiring diagram of an electric circuit used for controlling the solenoid valve; and

Fig. 13 is a diagrammatic view of the solenoid valve;

In general the dispenser comprises a plurality of magazines for retaining the sticks in side by side stacked relation, stick feeder means associated with each magazine to effect ejection of a stick forwardly from the magazine, means for controlling the actuation of the stick feeders and means mounted adjacent the front of the feeders movable between opposed positions and capable in each position of receiving and guiding the sticks ejected from the magazine to a position in which they are held to be readily inserted in stick receiving apertures in a stick holder such as disclosed in United States Patent 2,232,196 to Ralph Anderson. The various components of the dispenser may be mounted on any suitable means such as a cabinet or housing 21. In this embodiment the magazines are mounted on an inclined plate 22 extending upwardly from an intermediate portion of the top of the cabinet 21, the stick feeding means is mounted on the plate 22 in a position to effect ejection of the bottom sticks in the magazines and the movable stick supporter means is mounted at the top of the cabinet 21 in front of the magazines.

Projecting forwardly of the plate 22 in substantially perpendicular relation are a plurality of supports forming a forward portion of the stick feeding means, each having the form shown in Figures 1, 2 and 4. These supports are arranged in six spaced vertical rows, each row con-

40

35

45

50

55

55

sisting of four supports. These supports each consist of a bottom bar 24 which is suitably attached at its rear to the plate as by a screw, not shown. The forward part of each bar is formed with a shoulder 27 beyond which a bearing face 28 is disposed at an angle with respect to the remainder of the bar so that the face 28 is in a substantially horizontal position when the support is secured to the plate 22 as shown in Fig. 4. The face 28 is recessed intermediate its edges as shown at 30 in Figure 1. Positioned on opposite sides of the bar 24 are upstanding fillets 29 which serve to maintain the sticks in vertical alinement on the bottom bar 24. The forward end of the bar is provided with a bridging member 31 having leg portions disposed on opposite sides of the bar and a portion 32 extending across the top of the bar in parallelism with the face 28. Preferably the bridging portion 32 extends beyond the end of the bar 24 as shown in Fig. 4. The member 31 includes an upstanding outwardly flared portion 33 extending above the surface 28 and forming a stick stop to prevent longitudinal movement of the stack of sticks during the feeding operation.

Each magazine is formed by elongated parallel side portions 36 and 37 interconnected at their back by a portion 38 and spaced apart to receive the sticks in a stacked relation. The side portions 36 and 37 are of substantially lesser width than the length of the sticks so that the sticks project from the forward edge of the magazine. As shown the extreme lower edges of the sides 36 and 37 are disposed on opposite sides of the bar 24. A pin 35 received in a notch 39 on the top of the bar 24 serves to space the sides 36 and 37 and to support the forward portion of the magazine on the bar 24. The notch 39 is spaced from the plate 22 so that the back portion 38 of the magazine rests on the plate 22. Adjacent the upper ends of the magazines is a bracket 41 mounted on the plate 22. The bracket is positioned so that the right hand magazine, as shown in Figure 1, rests on the bracket and each succeeding magazine rests on the adjacent magazine and are inclined in a conventional manner. As illustrated the magazines are supported solely by the bracket 41 and the bottom bar 24 associated with the bottom of each magazine. With this construction and arrangement of the magazines the forward end of each stick rests on the bearing face 28 in a position such that when the stick is moved forward it will pass through the feed opening defined by the member 32 and the bearing surface 28. The magazines may be easily removed from the dispenser and replaced which is advantageous insofar as servicing of the dispensing unit is concerned.

Projecting rearwardly from the plate 22 in substantially perpendicular relation thereto are spaced rods 42 and 43 (see Fig. 6). At one end the rods are formed with portions of reduced cross sectional area receivable in apertures 44 and 46 in the plate 22. At their opposite ends the rods 42 and 43 also have portions of reduced cross sectional area received in spaced apertures 47 and 48 in a bracket 49. Nuts 51 and 52 threaded on the ends of the rods secure them in rigid relation with the bracket 49. The rod 43 is longer than the rod 42 for a purpose to presently appear. The bracket 49 is mounted on an angle iron 53 extending between and supported by opposite sides 54 and 55 of the cabinet 21. A feed plate 56 in substantial parallelism with the plate 22 is mounted on the rods 42 and 43 at the rear

of the plate 22 for movement toward and away from the plate 22. Suitable bearing members retained in bosses 57 and 58, rigid with the plate 56, embrace the rods as shown to slidably support the plate on the rods. By utilizing two bearings as shown the plate is not only positively guided in its movement toward and away from the plate but is also prevented from rotating or twisting. A bumper 59, in the form of a rubber washer, is mounted on the rod 43 between the end of the boss 58 and the bracket 49. The bumper 59 reduces shock on the parts when the feed plate 56 moves to its rearward position as shown in Fig. 6.

Attached to the forward side of the feed plate 56 is a plurality of push rods 61 as shown in Figs. 4 and 6, these rods being equal in number, i. e., six rows of four spaced rods, to the number of stick feeders and projecting through openings 62 in the plate 22. Lock nuts 60 on each push rod 61 abutting against opposite sides of the feed plate 56 secure the push rods in position on the plate. Each of these rods has a flattened upper face 63 (Figs. 4 and 6) terminating in a shoulder 64 which in turn joins a diagonal surface 66 terminating in an end 67. The shoulder 64 serves to engage the end of a stick and is substantially equivalent to or slightly less than the thickness of a stick so that when the rods 61 are pushed forward the shoulder 64 of each rod engages only a single stick. The shoulders 64 of all the rods are substantially in parallelism so that when the feed plate 56 occupies its rearmost position as shown in Fig. 6 each shoulder will be substantially flush with the forward surface of the plate 22.

The feed plate 56 is operated by a fluid operated piston unit 68. Any conventional piston and valve unit, of which numerous are to be had in the open market, may be used for driving the feed plate. One commercial form suitable for the purpose is shown in Fig. 6 and includes a cylinder 69 and a piston 71. The piston unit is disposed rearwardly of the feed plate 56 and is supported on the bracket 49. One end portion of the cylinder 69 is of reduced cross sectional area and products through an opening 70 in the bracket 49. A lock nut 72 threaded on the portion of the cylinder extending through the bracket abuts against the bracket 49 and secures the piston unit in position. The piston 71 is connected to an intermediate portion of the feed plate by a shaft 73 and lock nuts 74 threaded on the shaft 73 and disposed on opposite sides of the feed plate 56. The cylinder 69 is formed with passageways 76 and 77 in communication with front and back ends respectively of a piston chamber 75.

A solenoid operated valve 78 mounted on the back end of the cylinder 69 controls the flow of pressure fluid to the passageways 76 and 77, respectively. The solenoid valve 78 may be of any conventional construction. For purposes of simplifying the drawings it is shown diagrammatically in Fig. 13 so that the flow paths of fluid through the valve may be readily visualized and includes a casing 81 having a chamber 82 formed therein, ports 83 and 84 connected with the passageways 76 and 77, respectively, and a port 86 in communication with a suitable pressure fluid supply 87 as by a conduit 88. Disposed in the chamber 82 is a valve element 93 movable between opposed positions. At opposite ends of the casing 81 are spring biased valves 91 and 92 normally urged to closed positions and movable to an open position to effect communication be-

tween the chamber 82 and atmosphere upon engagement of the valve element 93 with shaft portions on the valves 91 and 92 in each of the positions of the valve element 93. The valve element 93 is moved by solenoid coils 96 and 97.

When the coil 96 is energized the valve element 93 is moved to assume the position shown in Fig. 13. In this position the element 93 closes the opening in the coil 96 shaped to receive an axially extending projection 85. Thus pressure fluid flows from the port 86 through the opening in the coil 97, shaped to receive an axially extending projection 90, to the port 84, to the passageway 77 to the back end of the chamber 75 and pressure fluid on the opposite side of the piston is discharged from the front end of the chamber 75 through the passageway 16, the port 83 and the spring biased valve 92, the opening of which is controlled by the valve element 93. When the coil 97 is energized the valve element 93 moves to assume a position at the right of that shown in Fig. 13 so that the element 93 closes the opening in the coil 97. Thus pressure fluid may flow from the port 86 through the opening in the coil 96, to the port 83, into the passageway 76 to the front end of the chamber 75 and the pressure fluid on the opposite side of the piston may be discharged from the back end of the chamber through the passageway 77, the port 84 and the spring biased valve port 91, the opening of which is under the control of the valve element 93.

The coils 96 and 97 are connected to a suitable source of power such as shown in Fig. 12. In this instance the power for the solenoid coils is supplied from the secondary of a transformer 101 disposed in a housing 100, the primary of which is connected to the main power supply. The coil 96 is connected across the secondary of the transformer 101 by a conductor 102 and a conductor 103. The coil 97 is connected to the secondary of the transformer 101 by a conductor 104 and conductor 103.

A normally open switch 106 controlling the forward movement of the feed plate 56 is connected in series with the conductor 102 to close the circuit to the coil 96. This switch is normally mounted on the top of the cabinet 21 at one side of the magazines as shown in Figure 1. To position the switch 106 so that it may be readily accessible by an operator of the dispenser, the switch is supported on the upper end of a conduit 107 rigid with the top of the cabinet 21. A normally open switch 108 controlling the reverse movement of the plate 56 is connected in series with the conductor 104. The switch 108 is mounted on the rear of the plate 22 as seen in Fig. 6. A bracket 109 attached to the feed plate 56 is positioned to engage the actuator of the switch 108 when the plate 56 moves to its extreme forward position. Thus the switch 108 forms a limit switch which effects energization of the coil 97 to return the feed plate 56 and push rods 61 to their retracted position at the conclusion of their stick ejecting or feeding movement. A normally open switch 111 is also connected in series in the conductor 102. This switch is mounted on the top of the cabinet 21 for a purpose to presently appear.

Provision is made for manual operation of the limit switch 108 to effect return of the plate 56 in the event that sticks jam in the stick feeders. The mechanism for this, see Figs. 5 and 6, comprises a rotatable shaft 112 extending through a suitable bearing member 113 supported by the side 55 of the cabinet. On its inner end the shaft 75

is formed with a depending tab 116 shaped to engage a plunger 117 of the switch 108. On its outer end is mounted a knob 114 for rotating the shaft 113 and forcing the tab 116 against the plunger 117. An end portion 119 of the shaft 112, at right angles to the main portion of the shaft, rests on the top of the housing of the switch 108 and provides a positioning means for the shaft 112.

One phase of the invention is concerned with novel means adjacent the front of the stick feeders capable of receiving the sticks ejected from the feeders and guiding them to a position in which they are clear of the feeders and are readily receivable in the stick receiving apertures of a conventional stick holder. As shown in Figures 1, 2 and 4 the means in this instance comprises a stick supporter which includes a plate 121 and a plurality of tubular members or stick guides 122 mounted on the plate in aligned rows, each having a spring 123 associated therewith to engage a stick and retain it in the tubular member so that an end portion thereof projects free of the tubular member 122. In this instance there are twelve aligned rows of stick guides each containing four spaced tubular members. As shown in Fig. 8 each tubular member 122 is disposed in a snug fitting aperture 124 formed in the plate 121. The end of the aperture 124 facing the stick feeders is flared as shown at 126. At their outer ends the tubular members 122 taper to define an elongated horizontal slot 127 capable of permitting the passage of one of the sticks. The spring 123 has one end disposed in an aperture 128 in the member 122 and bent back on itself to define anchor portions gripping the side wall of the tubular member 122 and an end projecting inwardly of the tubular member 122 through the aperture 129. Preferably the inwardly projecting end 130 of the spring 123 terminates in an arched portion as shown in Fig. 8 which normally extends above the centerline of the tubular member so that upon passage of a stick through the tubular member the spring is biased downwardly by the stick and the resiliency of the spring is such that the stick is held in the tubular member 122.

In Fig. 10 there is shown an alternative construction for the stick guides. In this instance the stick guides are formed by tubes 131. The latter project through apertures 135 formed in a tube support plate 132. At one end the tubes are flared outwardly as shown at 133 and at their opposite ends the tubes taper to define an elongated horizontally disposed slot 134. Each of the tubes 131 is formed with a slot 136 on one side. A coil spring member 137 is mounted to have a portion received in the slot 136. With this construction the stick is held in the tube 131 by engagement of the spring 137 with the side of the stick. To simplify the assembly the tubes 131 may be arranged as shown in Fig. 11 with the slots 136 of tubes in one row in alignment and facing the slots in an adjacent row. The springs 137 may be made long enough to span two tubular members as shown in Figure 11. Thus with this construction adjacent spring members 137 may be mounted by a common mounting bracket 138 secured to the plate 132 by a screw 139 between the rows of tubes.

The stick guide support plate 132 is suitably mounted for movement between opposed feed positions in front of the stick feeders. The plate 121 has pivot brackets 141 at opposite edges thereof rotatably mounted on a horizontally dis-

posed shaft 142. Spaced brackets 143 on the top of the cabinet 21 rigidly support the shaft 142. The brackets 143 are spaced apart a sufficient distance so that in one position of the plate 121 alternate rows of the stick guides 122 are in alignment with the stick feeders and in the other position the remaining rows of the stick guides 122 are in alignment with the stick feeders (see Figs. 2 and 3). To insure that the plate 121 is in its respective positions a cam 144 is mounted on the bottom of the plate to actuate the switch 111 connected in the circuit to the coil 96. Unless the plate 121 is in position to effect alignment of rows of stick guides with the stick feeders the circuit to the coil 96 is open and the stick feeders cannot be operated. Thus, as shown in Fig. 7, the depending portion 148 of the cam 144 engages the actuator 147 of the switch 111 when the plate is in its left hand position (solid line position) to close the switch 111 and the depending portion 148 on the opposite end of the cam 144 engages the actuator 147 in the other position of the plate 121 to close the switch 111. The latter position of the parts is shown by dotted lines in Fig. 7. The plate 121 is also rotatable about the shaft 142 from a position in which it is in substantially parallel relation with the plate 22 as shown in Fig. 4 and a position in which it is out of the way so that access to the stick feeders may be had. These positions of the plate are shown by the solid and dotted lines respectively in Fig. 4. The plate 121 is normally held in a position parallel to the plate 22 by a latch means. In general the latch means includes a bracket portion 152 secured to the face plate 22 so as to project outwardly therefrom. On its outer end the bracket is formed with a portion 153 pivotally mounted as by a pin 154 on the end of the bracket 152 for movement between the full line position and the dotted line position shown in Fig. 4. Projecting downwardly from the portion 153 are spaced rollers 156 suitably mounted on the portion 153 and shaped to engage opposite sides of a guide block 157 rigidly secured to the upper edge of the plate 121. The rollers 156 are spaced apart a sufficient distance to permit straddling of the guide block 157. This construction positively holds the upper edge of the plate 121 in fixed relation while at the same time permitting lateral movement thereof between the opposed positions. When the plate 121 is in the dotted line position as shown in Fig. 4, the pivot brackets 141 engage the shoulders 159 formed on the brackets 143 to support the plate, one shoulder only being engageable with the one pivot bracket 141 in each of the positions of the plate 121. The latter is formed with spaced lower forwardly projecting lugs 161 and upper support members 162 and 163 for the stick holder. The latter are spaced and arranged to provide a support and locating means for the stick holder adjacent the ends of the stick guides 122. The guide 163 is adjustable to effect proper alignment of the stick holder on the plate 121.

The operation of the dispensing mechanism is readily apparent from the foregoing but may be briefly summarized as follows: The operator places the stick holder on the stick holder lugs 161 and guides 162 and 163 on the plate 121 with the stick holder and plate 121 occupying one of the preselected positions of the plate 121. For purposes of illustration assume that the plate 121 occupies the position on the right as shown in

Fig. 2 and in solid lines in Fig. 7. Under these conditions the depending portion 148 of the cam 144 engages the actuator 147 to actuate the switch 111. The operator then depresses the push button on the switch 106 to momentarily energize the coil 96. Energization of the latter causes the valve element 93 to move to a position (see Fig. 13) such that pressure fluid flows into the passageway 71, to the back end of the chamber 75 and pressure fluid on the opposite side of the piston is exhausted from the front end of the chamber 75 through the passageway 76 and the valve 92 and the feed plate 56 and the push rods 61 move forward. As a consequence the bottom stick of each magazine is ejected and is directed into the tubular guides 122 directly in front of the respective feeders. At the end of the forward movement of the plate 56, the bracket 109 effects actuation of the limit switch 108, whereupon the coil 97 is momentarily energized. Actuation of the coil 97 moves the valve element 93 to a position such that pressure fluid is directed through the passageway 76 to the back end of the chamber 75 and pressure fluid on the opposite side of the piston 71 is exhausted from the chamber 75 through the passageway 77 and valve 91. The feed plate then moves to its retracted position (see Fig. 6). Thereafter the operator moves the stick guide support plate 121 from the position shown in Fig. 2 to the position shown in Fig. 3 and dotted line position in Fig. 7. The depending portion 148 engages the actuator 147 and closes the switch 111 in the circuit to the coil 96. The push button on the switch 106 is again depressed to actuate the switch 106. The push rods 61 move forwardly and eject the bottom sticks from the respective magazines as before and urge the same respectively into the alternate rows of the stick guides 122. The stick guides 122 are now filled with sticks, and are holding them in a position to be readily received by the stick holder. The operator can grip the ends of the sticks projecting from the stick guides by manipulation of suitable means on the stick holder. Thereafter the sticks may be withdrawn in unison from the stick guides 122 and carried to the molds or other desired location. It is to be understood that at the conclusion of the forward movement of the plate 56, the bracket 109 actuates the switch 108 and effects return of the push rods 61 to their retracted position as before.

With this construction the capacity of the stick holder may be doubled without increasing the number of stick feeders. By doubling the capacity of the stick holder manual handling of the sticks between the dispenser in the molds is in effect halved.

It frequently happens that a stick is warped so badly that it cannot pass through the stick feeders or guides 122 and consequently causes a jamming of the parts. With this construction should the above happen, the operator can reverse the direction of movement of the push rods 61 by turning the knob 114. This operates the switch 108 and energizes the circuit to the coil 97 which controls the position of the valve element 93 which in turn directs pressure fluid to the piston unit to return the push rods 61 to their position shown in Fig. 6. The latch means for the plate 121 and subsequently the plate 121 may be moved to the dotted line position shown in Fig. 4. In this position of the parts the stick feeders are readily accessible for service and maintenance purposes.

I claim:

1. In a stick dispenser, the combination of a plurality of rows of spaced stick feeders, a stationary base disposed adjacent said stick feeders, a support, means mounting said support on said base to limit the displacement of the support between spaced limiting positions on the base, said support in one of said limiting positions being disposed adjacent the front of said feeders and movable relative to the rows of feeders between opposed loading positions, and a plurality of rows of spaced stick guiding and holding means positioned on said support to have alternate rows in alignment with said rows of stick feeders in each of said loading positions of the support to position and hold sticks ejected by the feeders for ready reception by a stick holder.

2. In a stick dispenser, the combination of a plurality of rows of spaced stick feeders, a stick supporter adjacent the front of said feeders, stick ejecting means for ejecting sticks from said feeders to a position in which they are clear of the feeders and are retained in the supporter to have one end of the sticks project beyond the supporter to be grasped by a stick holder, means for mounting said stick supporter for movement between opposed loading positions to align alternate portions of said supporter with said feeders, and means preventing the stick ejecting operation of said stick ejecting means except when said stick supporter is positioned in one of said loading positions.

3. In a stick dispenser and the like, the combination of a plurality of aligned rows of spaced stick feeders for dispensing sticks, a plate having a plurality of rows of apertures, stick guide means mounted in each of said apertures for receiving and holding the ejected sticks in a position to be pulled therefrom by a stick holder, and means mounting said plate for bodily movement angularly about an axis between a position in which the plate is disposed adjacent the ends of the feeders and a position in which the plate is remotely disposed with respect to the feeders to permit access thereto.

4. In a stick dispenser and the like, the combination of a plurality of aligned rows of spaced stick feeders mounted on a support, a plate having a plurality of apertures, a stick guide means mounted in each of said apertures for receiving and holding the ejected sticks in a position to be simultaneously pulled therefrom by a stick holder, spaced brackets mounted on said support adjacent opposite ends of said plate, a shaft supported at opposite ends by said brackets and pivot brackets each having a portion mounted on said shaft for rotational and axial sliding movement and a portion rigidly connected with the plate, said plate being free to move between opposed loading positions to align alternate rows of the stick guide means with the stick feeders and rotatable between a position in which the stick guide means are adjacent the stick feeders to receive sticks ejected therefrom and a position in which they are remotely disposed from the stick feeders to permit access to the latter.

5. In a dispenser having a stick feeder, the combination of a support, a stick guide comprising a tubular member mounted on said support having an end shaped to receive a stick from said feeder and an end having a preshaped opening conforming to the cross sectional configuration of the sticks, said tubular member having a slot formed on one side, a coil spring having a

portion disposed in said slot to engage the side of a stick received in said tubular member and means for mounting said coil spring on said support to permit flexing of said portion upon reception of a stick in said tubular member and to bias said spring to hold the stick in said tubular member.

6. In a dispenser having a plurality of stick feeders, the combination of a support, a pair of stick guides mounted on said support each comprising a tubular member having an end shaped to receive sticks from said feeders and an end having a preshaped opening conforming to the cross sectional shape of the sticks, said tubular members each having a slot and positioned on said support to have the slots on the same side of the tubular members, and spring means having a portion disposed in each of said slots to engage the sides of sticks received therein, said portions being flexible upon engagement thereof by sticks to bias the latter to positively hold said sticks in the tubes, said spring means also having a portion confined between said tubular members and the support for securing said spring means to the support and said portions in said slots respectively.

7. In a stick dispenser and the like, the combination of a plurality of magazines for supporting the sticks, means including a push rod associated with each magazine for ejecting sticks therefrom, a feed plate for mounting said push rods movable between positions in which the push rods are in a retracted position with respect to the magazines and an advanced position in which sticks are dispensed from the magazines by the rods, a pressure fluid piston unit for moving said plate between said positions, valve means between the pressure fluid piston unit and a source of pressure fluid for selectively controlling the flow of pressure fluid to said pressure fluid piston unit and means operated in response to movement of said feed plate and rods to said advanced position for actuating said valve means to return the feed plate to retracted position.

8. In a stick dispenser and the like, the combination of a plurality of rows of stick feeders including a feed plate movable between a first and a second position, a pressure fluid unit including a cylinder and a piston reciprocably disposed in the cylinder to effect the above movement of the plate, solenoid valve means including a first solenoid coil for controlling the flow of pressure fluid to one end of the cylinder and a second solenoid coil for controlling the flow of pressure fluid to the opposite end of the cylinder, a first electric circuit for connecting said first solenoid coil to a source of power, a first switch connected in said first circuit for controlling the energization of said first solenoid coil to effect movement of the plate from said first to the second position, a second electric circuit for connecting said second solenoid coil to a source of power, a second switch connected in said second circuit for controlling the energization of said second solenoid coil, and means on said plate operable to actuate the second switch in the second position of the plate to energize said second circuit and effect return of the plate to its first position.

9. The combination recited in claim 8 with a housing for enclosing the second switch and manual means accessible from the exterior of the housing for actuating the second switch to effect movement of the plate back to its first position.

10. In a stick dispenser and the like, the combination of a plurality of stick feeders including push rods movable between a first and a second position to effect ejection of said sticks from the feeders, power operated means for moving said push rods between said positions, manual means controlling the power operated means to initiate movement of the push rods from the first to the second position, means for controlling the power operated means to initiate return of the push rods from the second to the first position in response to movement of the push rods into the second position, and manual means operable to control the power operated means to effect return of the push rods from an intermediate position to the first position.

11. In a stick dispenser, the combination of a plurality of rows of spaced stick feeders, each including a magazine for retaining sticks and means for ejecting the sticks from the magazines to a position in which they are spaced from the magazine, and a stick supporter adjacent said feeders shaped to receive and guide said sticks as they are ejected from the feeders to a position in which portions of the stick project beyond the supporter for reception by a stick holder, said supporter being mounted for axial movement between opposed loading positions to align different portions of the supporter with the feeders and being pivotally mounted for movement between a position in which the supporter is adjacent the stick feeders and a position in which the supporter is remote from the stick feeders to permit access to the stick feeders.

12. In a stick dispenser and the like, the combination of a plurality of stick feeders including push rods movable between retracted and extended positions to effect ejection of said sticks from the feeders, power operated means for moving said push rods between said positions, opera-

5 tor-controlled means controlling the power operated means to initiate movement of the push rods from the retracted to the extended position, and operator-controlled means operable to control the power operated means to effect return of the push rods to the retracted position from an intermediate position between said retracted and extended positions.

10 13. In a stick dispenser and the like, the combination of a plurality of stick feeders including ejectors movable between retracted and extended positions for ejecting the sticks from the feeders, power operated means for moving said ejectors between said positions, operator-controlled means controlling the power operated means to initiate forward movement of the ejectors from the retracted to the extended position, said power operated means upon forward movement of the ejectors to the extended position automatically returning said ejectors from the extended to the retracted position, and operator-controlled means controlling said power operated means to return the ejectors to the retracted position when the ejectors in moving forward stop at an intermediate position between the retracted and extended positions.

RALPH F. ANDERSON.
